UNITED STATES PATENT OFFICE.

ISAAC A. BACKLUND, OF SATRA, SWEDEN.

DAMPER REGULATOR.

Application filed April 13, 1926. Serial No. 101,839.

This invention relates to regulators for the flue dampers of steam boiler furnaces of that type adapted to be controlled by the pressure in the boiler and adapted to move the damper in the direction of its fully closed position as the pressure increases and in the direction of its fully opened position as the pressure decreases.

The invention has for one of its objects 10 to improve damper regulators of this character to the end that they will be more sensitive and positive of operation and to the end that a single device may be employed for the purpose of controlling a plurality 15 of engines.

With the foregoing and other objects in view, the invention consists of the novel construction, combination and arrangement of parts hereinafter fully described and 20 claimed and illustrated in the accompanying drawings, wherein:

Figure 1 is a sectional view taken on a plane extending vertically through a damper regulator embodying my invention, and 25

Figure 2 is a similar view of a slightly modified form of the invention.

In the drawing, 1 designates the discharge flue of a steam boiler furnace, 2 a damper mounted in the flue 1 for movement about a 30 horizontal axis by means of a shaft 3, and 4 a lever connected at one end to an end of the shaft 3.

The present invention embodies a vertically disposed engine 5 which consists of 35 a cylinder 6, piston 7 and rod 8. The upper end of the rod 8 is connected to the outer end of the lever 4 by a link 9. A vertical frame 10 passing about the cylinder 6 and secured at its upper end to the rod 8, is provided 40 at its lower end with weights 11 which function to normally maintain the damper 2 in its fully opened position and the piston 7 in its lowermost position. The cylinder 6 is provided at a point below the lowermost 45 position of the piston 7 with an inlet and discharge port 11. A vertically disposed valve 12 controls the admission of fluid pressure to and its discharge from the engine 5, and consists of a cylinder 13, relatively 50 spaced pistons 14, and a rod 15 to which the pistons 14 are connected. The cylinder 13 is provided with an intake port 16 and a discharge port 17, and a pipe 18 establishes communication between the cylinder 13 and 55 the port 11 of the engine 5. A pipe 19 communicates with the intake port 16 and with

a pipe 20 extending from any suitable source of supply of pressure fluid. A pipe 21 extends from the discharge port 17 to a pipe 22 discharging in a sewer, reservoir or trap. The pistons 14 of the valve 12 are under the control of a vertically disposed engine 23 which consists of a cylinder 24, piston 25 and rod 26. A lever 27 pivoted at one end as at 28, has its free end loosely connected to the rod 26 as shown at 29, and the rod 15 is connected as at 30 to the lever 17 at a point between the ends of the latter. A frame 31 extending vertically about the cylinder 24 is connected at its upper end to the rod 26 and carries at its lower end weights 32 which function to normally maintain the piston 25 in its lowermost position and pistons 14 in the position shown. The cylinder 24 is provided at a point below the lowermost position of the piston 25 with an intake and discharge port 33. The admission of pressure fluid to and its discharge from the engine 23 is under the control of a valve 34 which is similar to the valve 12 and consists of a cylinder 35, relatively spaced pistons 36 and a rod 37 to which the pistons are secured. This cylinder is provided with an intake port 38 and a discharge port 39, and communication between it and the port 33 of the engine 23 is established by means of a pipe 40. A pipe 41 communicates with the discharge port 39 and discharge pipe 22, and a pipe 42 communicates with the intake port 38 and pressure fluid supply pipe 20. The pipes 19 and 42 are provided with valves 43 and 44, respectively. A lever 45 pivoted at one end as at 46 is connected between its ends as at 47 to the rod 37, and carried by the lever 45 adjacent its free end are weights 48 which function to normally hold the pistons 36 in the position shown. An engine 49 comprising a casing 50, a diaphragm 51, and a rod 52 connected to the diaphragm 51 and lever 45, function to rock the lever upwardly when the pressure of the steam is great enough to overcome the weights 48. This engine is in communication with the steam space of the boiler by way of a pipe 53. A vertically disposed engine 54 controls a weight 55 and is under the direct control of the valve 12. It comprises a cylinder 56, piston 57 and rod 58. A cable 59 secured at one end to the rod 58 passes over a pulley 60 and has secured to the other end thereof a frame 61 through which the free end of the

lever 45 passes and to which the weight 55 is secured. A frame 62 extends about the engine 54 and is secured to the rod 58. Weights 63 are secured to the lower end of the frame 62 and function to normally maintain the piston 57 in its lowermost position. The cylinder 56 is provided at a point below the lowermost position of the piston 57 with an intake and exhaust port 64 which is in communication with the pipe 18 by way of a pipe 65. This pipe is provided with a valve 66. To permit of damper regulators, consisting merely of engines similar to the engine 5, to be controlled by this apparatus, a pipe 67 is provided. This pipe is in communication with the pipe 18 and is provided with a valve 68.

In practice, the parts of the device normally occupy the positions shown in the drawing and the valves 43, 44 and 66 are opened. The engines 5 and 54 are in communication with the discharge pipe 22 by way of the pipes 18, 65, exhaust port 17 of valve 12 and pipe 21, and the engine 23 is in communication with said discharge pipe by way of the pipe 40, exhaust port 39 of valve 34 and pipe 41. When the steam pressure is sufficient to overcome the weights 48, the engine 49 will function to raise the pistons 36 of the valve 34 with the result that communication between the pipes 40 and 41 will be cut off and communication between the pipes 40 and 42 established. Pressure fluid will now flow by way of the pipes 20 and 42, valve 34 and pipe 40 to the engine 23. The resulting movement of the piston 25 will operate the pistons 14 of the valve 12 in a manner to cut off communication between the pipes 18 and 65 and the pipe 21, and establish communication between the pipes 18 and 65 and the pipe 19. Pressure fluid will now flow through the pipes 20 and 19 to the valve 12 and from the valve 12 to the engines 5 and 54 by way of the pipes 18 and 65. The resulting movement of the piston 7 of the engine 5 and the piston 57 of the engine 54 will move the damper 2 in the direction of its closed position and lower the frame 61 and weight 55. The degree of movement of the damper 2 in this direction will depend solely on the pressure of the steam. This operation of the piston 57 increases the weight on the lever 45 due to the fact that the frame 61 is lowered into contact with the lever, with the result that when the pressure of the steam falls the lever 45 will be promptly moved into normal position. The movement of this lever into this position will operate the pistons 36 of the valve 34 in the reverse direction, establishing communication between the engine 23 and discharge pipe 22 by way of the pipe 40, valve 34 and pipe 41. The weights 32 will now operate the valve 12, and as the result establish communica-

tion between the engines 5 and 54 and the discharge pipe 22 by way of the pipes 18 and 65, valve 12 and pipe 21. The weight 11 will now move the damper 2 in the direction of its closed position and the weight 63 will move the weight 55 in the direction of its normal position in which latter position the frame 61 is out of contact with the lever 45.

The regulator shown in Figure 2 differs but slightly from the one shown in Figure 1, and corresponding parts of both regulators are designated by similar reference characters. The regulator shown in Figure 2 is simpler than the one shown in Figure 1, and this simplicity in construction was brought about by substituting a combined valve and engine 12^a for the valve 12, engine 23 and connection 27 between the valve 12 and engine 23. The combined engine and valve 12^a comprises a cylinder 13^a, relatively spaced pistons 14^a and a rod 15^a to which the pistons are secured. A frame 31^a is secured to the piston rod 15^a and has secured thereto weights 32^a. The cylinder 13^a is provided with an intake port 16^a and a discharge port 17^a with which the pipes 19 and 21 communicate. The cylinder 13^a is provided below the lowermost piston 14^a with a port 33^a with which the pipe 40 communicates, and is connected to the engine 5 by way of the pipe 18. As the operation of this form of the regulator is substantially the same as that of the regulator shown in Figure 1, a further description of this regulator is deemed unnecessary.

From the foregoing description, taken in connection with the accompanying drawings, the advantages of the construction and of the method of operation will be readily apparent to those skilled in the art to which the invention appertains. While I have described the principle of operation of the invention, together with the device which I now consider to be the best embodiment thereof, I desire to have it understood that the device shown is merely illustrative, and that such changes may be made when desired as are within the scope of the invention as claimed.

What is claimed is:—

1. A device of the character set forth, comprising, in combination with a damper, an engine for operating the damper, a valve for controlling the admission and discharge of pressure fluid to and from the engine, means for controlling said valve and adapted to be operated by fluid pressure and a weight, and a second engine under the control of said valve for normally supporting said weight.

2. A device of the character set forth, comprising, in combination with a damper, an engine for operating the damper, a valve for controlling the admission and discharge

of pressure fluid to and from the engine, means for controlling said valve and adapted to be operated by pressure fluid and a weight, a second engine under the control of the 5 valve, and a weight under the control of the second engine and adapted when said means is operated by pressure fluid to add weight thereto.

3. A device of the character set forth, 10 comprising, in combination with a damper, an engine for operating the damper, a valve for controlling the admission and discharge of pressure to and from the engine, means for operating the valve and adapted to be 15 operated by pressure fluid and a weight and embodying a lever, a second engine under the control of the valve, a member adapted to be moved with respect to the lever by the second engine, and a weight carried by the 20 member, said member being lowered into

contact with said lever when said means is operated by fluid pressure and raised out of contact with said lever when said means is operated by its weight.

4. A device of the character set forth, 25 comprising, in combination with a damper, an engine for operating the damper, a valve for controlling the admission and discharge of pressure fluid to and from the engine, a second engine for operating the valve, a 30 second valve for controlling the admission and discharge of pressure fluid to the second engine, means for operating the second valve and including a lever and a weight, and an engine under the control of the first valve 35 for normally supporting the weight of the lever.

In testimony whereof I affix my signature.

ISAAC A. BACKLUND.
